GEORGE W. WILSON, OF CHELSEA, MASSACHUSETTS.

Letters Patent No. 65,784, dated June 11, 1867.

IMPROVEMENT IN AIR-HEATING FURNACES.

The Schedule referred to in these Letters Patent and making part of the same.

TO ALL PERSONS TO WHOM THESE PRESENTS SHALL COME:

Be it known that I, GEORGE W. WILSON, of Chelsea, in the county of Suffolk, and State of Massachusetts, have invented an improved Air-Heating Furnace for warming buildings; and do hereby declare the same to be fully described in the following specification, and represented in the accompanying drawings. Of such drawings—

Figure 1 is a front end view.

Figure 2, a rear end elevation.

Figure 3, a side elevation.

Figure 4, a longitudinal section; and

Figure 5 a transverse section of such furnace.

The said furnace is to be constructed mostly if not entirely of cast iron, and when used is, with the exception of its front end-plate, to be enclosed in an air-receiving chamber provided with suitable inlets or passages and outlets, whereby air, while flowing through such chamber, may be heated by means of the said furnace.

In the drawings, A denotes the fire-place, or chamber of combustion, and B the ash-chamber, the former being arranged over the latter, and being provided with a rotary grate, C. The chamber A is arched at top, and has long passages *a a* leading out of it laterally, and from its opposite sides into and through two abutments, D D, which are extended from and cast in one piece with the fire-place, and serve as supports for an arched-radiator, E, which spans the dome or arch of the fire-place concentrically or thereabouts, there being an air-heating space, F, between the two. The said space is open at its two extremities. The said radiator E opens at its top by a conduit, *b*, into another radiator, G, situated over it, and provided with pipes, *c d*, to project from and open out of its opposite ends. One of such pipes opens through the front plate H of the furnace by a man-hole, *e*, provided with a cover, *f*. The other of such pipes has a damper, *g*, placed within it, such damper having a rod, *h*, to extend from the crank-arm *i* of the shaft, and to and, through the said front plate. Two elbow pipes *I I* lead laterally out of the front part of the auxiliary radiator G, and into two U-shaped conductors or radiators *K K*, arranged with respect to the main radiator and the front plate in manner as represented in the drawings. Each leg of each U-shaped radiator may open through the front plate and be provided with a cover, such being to enable the interior surface of the U-shaped radiator to be cleaned as occasion may require. Each of the two U-shaped radiators *K K* communicates near its front end, by a branch pipe, *i'*, with one of two bent pipes *L L*, formed and arranged with the U-shaped radiator as represented. Each of the pipes *L L* opens at its front end through the front plate H, the opening being provided with a cover. At its other end the pipe *L* leads or opens into the rear pipe *d* of the radiator G. An escape pipe, *M*, is to lead out of the top of the pipe *d*, such pipe *d* at its rear end being open and extended through the brick-work of the air-chamber. When the furnace is in operation the mouth or rear end of the pipe *d* is to be closed by a cover. A conduit, *N*, leads out the rear end of the ash-chamber, and may extend to the outside of the brick-work in which the furnace may be encased. A stand pipe, *O*, erected on the pipe *N*, and opening out of it, opens at top into the pipe *d*, and is provided with a damper, *k*, which is arranged and furnished with an operating rod, *l*, as shown in the drawings, (fig. 4.) Within the main radiator is a scraper, *P*, which extends across it, and is affixed to a slide-rod, *Q*, going horizontally through the radiator and the front plate H. By means of such rod the scraper may be moved from end to end of the radiator, and upon its inner surface, in order to cleanse it of soot or ashy deposits and cause such to fall into the fire-place. The grate C of the fire-place has its journals *l m* extended through and supported by two swing-plates *R R*, arranged at opposite parts of the fire-place in manner as represented in fig. 4. Each of such plates extends across and forms part of the fire-place, and at its upper corners is provided with journals *n n*, to rest in suitable bearings, the whole being to enable the said plates with the grate to swing back and forth, in order that, by such a movement of the grate, cinders and ashes when thereon may be shaken through it into the ash-chamber, and upon its grate *y*. On opposite sides of the fire-place mouth *p* are two air-inlet registers, *s s*, for letting air into the flame as it may rush out the passages leading through the abutments on which the main radiator is supported.

In the operation of this furnace the smoke and volatile products of combustion pass from the fire-place

through the abutments, and into the main radiator. Circulating therein, they heat its curved top and bottom whereby heat will be radiated therefrom into the space between the radiator and the arch of the fire-place, and also that over the radiator. As the space between the said radiator and the front plate H of the furnace is open in front, and as also such space is open in rear, the air of the hot-air chamber can circulate freely through it. The smoke passes from the main into the auxiliary radiator, and from thence it may be allowed to escape directly through its pipe, d, or by closing the damper in such pipe the smoke may be made to flow into the U radiators, and from thence into and through the bent pipes L L, and thence into the escape flue, the said smoke, in its passage through such pipes, heating them, whereby they will radiate heat into the surrounding air. By closing the damper of the pipe d, and opening that of the stand pipe O, the smoke and volatile products of combustion may be caused to pass through the fuel and the grate of the fire-place into the ash-chamber, and thence into and through the stand pipe, rather than the several radiators. In this way, the heat of a fire, when it may not be desirable to carry the smoke through the radiators, may be discharged through the stand pipe.

Having thus described my said furnace, what I claim therein as of my invention, is as follows.

I claim the arrangement as well as the combination of the main radiator E, the fire-place A, the hollow abutments, and the air-space between the fire-place and main radiator.

I also claim the combination as well as the arrangement of the auxiliary radiator G, the main radiator, the fire-place, the air-space F, and the abutments D D for supporting the main radiator, and conducting smoke into it from the fire-places.

I also claim the combination as well as the arrangement of the U radiators and the bent pipes L L with the fire-place or chamber of combustion, and either or both the radiators arranged as specified.

I also claim the application of the grate to the fire-place by means of the pendulous plates applied to the journals of such grate, and to the fire-place, substantially as set forth.

I also claim the combination and arrangement of the scraper P and its rod Q with the main arched radiator and the front plate H, as explained.

I also claim the arrangement of air-registers with respect to the fire-place, the escape-passages thereof, and the front plate H, the whole being substantially as hereinbefore specified.

GEO. W. WILSON.
